UNITED STATES PATENT OFFICE

HARRY E. BARROWS, OF SHEBOYGAN, WISCONSIN, ASSIGNOR TO DILLINGHAM MANUFACTURING CO., OF SHEBOYGAN, WISCONSIN, A CORPORATION OF WISCONSIN

COMBINATION STOOL AND STEPLADDER

Application filed May 26, 1928. Serial No. 280,874.

My invention relates to new and useful improvements in furniture and more particularly to a combination stool and stepladder, the principal object of the invention residing 5 in the provision of a device of the character described embodying features of ornamentation as well as utility, being relatively simple and inexpensive in construction and of a size whereby it may be easily carried from 10 place to place.

Another object of the invention consists in the provision of a device of the character described having a movable top which, when in lowered position, forms a seat for the stool 15 and, when in raised position, is in easy reach to act as a hand-hold or grip to aid in the support and steadyng a person ascending or descending the stepladder, means being provided for holding the top in its raised position.

With the above and other objects in view, which will appear as the description proceeds, my invention consists in the novel details of 25 construction, and arrangement of parts, described in the following specification and illustrated in the accompanying drawings, and while I have illustrated and described the preferred embodiments of the invention, as they now appear to me, it will be understood 30 that such changes may be made as will fall within the scope of the appended claims.

In the drawings:

Fig. 1 is a perspective showing the top in raised position.

Fig. 2 is a perspective showing the top in its lowered position.

Fig. 3 is a front elevation with the top in raised position.

Fig. 4 is a vertical section with parts shown 40 in side elevation; and

Fig. 5 is a fragmental detail showing a rear elevation with the top in lowered position.

In the drawings 1 indicates the supporting legs, 2 the side braces extending between the 45 front and rear legs, and 3 the back braces extending between the two rear legs. The side braces 2 form a support for the steps 4, 5 and 6 and secured to the upper surface of each of the steps is a pad 7 of rubber or similar material.

A top 8 is connected to a pair of legs 1, as shown in the drawings, the right hand legs, by means of the hinges 9 or other suitable connections. While I have illustrated the top as connected to the right hand legs it will be understood that they could equally as well be attached to the left hand pair of legs and the top will function in the same manner and for the same purposes. When the top is in lowered position it will extend horizontally as shown more particularly in Figs. 2 and 5 of the drawings and when in raised position will extend vertically as shown more particularly in Figs. 1, 3 and 4 of the drawings.

A toggle joint brace 10 is connected to the rear edge of the upper step 6 and to the under surface of the top 8, as shown more particularly in Figs. 1, 3, 4 and 5 of the drawings and is adapted for holding the top in its raised or vertically extending position. As the toggle joint brace is of ordinary and well-known construction a further detail description thereof is not thought necessary.

From the above detail description it is thought that the construction of my combined stool and stepladder will be clearly understood as well as the manner in which the top may be raised and lowered. When used as a stool the top will be in its lowered position as quite clearly illustrated in Figs. 2 and 5 of the drawings and may be used as a seat, it being understood that it will be on a plane or height adapting it for this purpose. When in lowered position the top will overlie the steps 4, 5 and 6 and such an ornamental appearance is obtained as to be pleasing to the eye and adapting the device for use in a kitchen or the like. When the device is to be used as a stepladder the top will be raised into the position shown more particularly in Figs. 1, 3 and 4 of the drawings, the swinging movement of the top being limited by the toggle joint brace 10 and the top being held by this brace, against accidental displacement, in the vertically extending position shown. A person ascending or descending the steps may grasp the top, preferably the upper edge thereof, with their hand and this will steady and support them against falling. The top, when raised, 100

is positioned at such a point as to be within easy reach of the person and, as I have previously stated, while I have illustrated the top as being on the right hand side of the 5 steps, as faced by the person, it will be understood that it could equally as well be connected on the left hand side. The combined stool and stepladder may be painted with any suitable color and with such ornamentations as may be desired.

Having fully described my invention what I claim as new and desire to secure by Letters Patent is:—

1. A combined stool and stepladder comprising a supporting structure including steps, and a member hinged to and adapted to extend upwardly from the supporting structure adjacent one end of the upper step and to the side of a person ascending or descending the steps in position to be readily grasped by the hand.

2. A device of the character described comprising a supporting structure including steps, and a member hingedly connected to one side of the supporting structure adjacent one end of the upper step and adapted to be raised and lowered, said member when in lowered position being positioned horizontally over the steps substantially within the 25 confines of the supporting structure and when raised being positioned to the side of a person ascending or descending the steps to be readily grasped by the hand.

3. A combined stool and stepladder comprising a supporting structure including steps, and a member hingedly connected at one side of the supporting structure, said member when lowered being positioned horizontally over the supporting structure and 30 when raised extending vertically to the side of a person ascending or descending the steps to be readily grasped by the hand, the line of pull on the member when grasped being at right angles to the longitudinal axis of the steps and in a direction at right angles to the movement of the member when being lowered to horizontal position.

In testimony whereof I hereunto affix my signature.
